UNITED STATES PATENT OFFICE.

ERNEST J. SEABURG, OF JAMESTOWN, NEW YORK.

DESIGN FOR A COMBINATION LIBRARY-TABLE AND PHONOGRAPH-CASE.

57,158.

Specification for Design.

Patented Feb. 22, 1921.

Application filed February 20, 1920. Serial No. 360,165. Term of patent 14 years.

To all whom it may concern:

Be it known that I, ERNEST J. SEABURG, a citizen of the United States, residing at the city of Jamestown, in the county of Chautauqua and State of New York, have invented a new, original, and ornamental Design for a Combination Library-Table and Phonograph-Case, of which the following is a specification, reference being had to the accompanying drawing, forming a part thereof.

The figure is a perspective view of a com-

bination library table and phonograph case showing my new design.

I claim:

The ornamental design for a combination library table and phonograph case as shown.

In testimony whereof I have affixed my signature in the presence of two witnesses.

ERNEST J. SEABURG.

Witnesses:
